Wilbur G. Houk.

Inventor:

UNITED STATES PATENT OFFICE.

WILBUR G. HOUK, OF CRAWFORDSVILLE, INDIANA.

BRAKE-LOCKING DEVICE.

SPECIFICATION forming part of Letters Patent No. 685,840, dated November 5, 1901.

Application filed April 4, 1901. Serial No. 54,381. (No model.)

To all whom it may concern:

Be it known that I, WILBUR G. HOUK, a citizen of the United States, residing at Crawfordsville, in the county of Montgomery and State of Indiana, have invented certain new and useful Improvements in Wagon and other Vehicle Brakes; and I do hereby declare the following to be a clear, full, and exact description of the same.

10 My invention relates to locking devices for wagon and other vehicle brakes, the object being to provide on the gear of the wagon or vehicle a simple and practical locking contrivance for the brakes of wagons and other vehicles; and it therefore consists in the construction, arrangement, and combination of the several parts substantially as will be herein-after described and claimed.

In the annexed drawings, illustrating my invention, Figure 1 is a skeleton view of the rear part of a wagon-gear with the parts of an ordinary wagon-brake as it is commonly used provided with my brake-locking device, the parts of the same being in a locked position. 25 Fig. 2 is a similar view of a wagon gear and brake provided with my improvement in an unlocked position. Figs. 3, 4, and 5 represent the separate parts of my invention.

Similar letters of reference designate corresponding parts throughout all the different figures of the drawings.

A designates an ordinary brake-roller suitably attached to the gear of a wagon, said roller being provided with a short arm a, which is 35 pivotally connected with rod B. The other end of rod B is connected to a swinging brake-beam C, which carries the shoes c and c, adapted to operate against the wheels D and D, all being used as an example merely to illustrate 40 the practical application of my improvement.

E designates a flat vertical arm with its lower end rigidly secured to brake-roller A. This arm E is provided near its lower end with a diagonal slot e, with lower end pointing to 45 the left or rear of arm E. Said arm has near its upper end a vertical slot e', corresponding in length to slot e. The upper end of arm E is convex, so as to fit the under concave edge of segment F. This segment F is fastened 50 rigidly to the gear of wagon, preferably to rear bolster G, by means of bolting through flange f on rear end of segment F. Said segment F

extends forward between parallel parts k and k of brake-lever H, with under edge of segment resting on top convexed end of vertical 55 arm E. The front portion of upper edge of segment F is provided with cog-shaped teeth f', angling to the right or forward, with the upper end of teeth convexed and spaces between them concaved. The rear portion of 60 upper edge of segment F is provided with a recess f''.

H designates a vertical brake-lever constructed of two parallel parts k and k, provided near its upper end with two horizontal 65 lever-rings h and h, with projections h' and h', which are inserted between the two parallel parts k and k, so as to bring the rear outer part of rings h and h to bear against front edge of parts k and k, all of which are 70 firmly riveted through and held in place by rivets i and i'. The lower ends of said parallel parts k and k of brake-lever H extend down on each side of segment F and vertical arm E and are secured to the latter by means 75 of bolts i' and i', extending through slots e and e' in vertical arm E in a manner that pivots brake-lever H to arm E at slot e', thereby allowing both ends of brake-lever H to oscillate back and forth and at the same time having an up-and-down movement relative thereto, governed by the corresponding lengths of 80 slots e and e' in arm E.

J designates a pawl pivoted to and swinging loosely between the parts k and k of 85 brake-lever H in the space just above segment F. The lower end of pawl J is forked, having an anterior prong j, convexed to fit in succession with the concaved spaces between the teeth f' on top edge of segment F; also, a 90 posterior prong j' of sufficient length to form, in connection with anterior prong j, a concaved space between prongs j and j', so as to fit any one of the upper convexed ends of teeth f' on top edge of segment F when my 95 device is being unlocked. It will be thus clearly seen that in order to lock a vehicle-brake with my improved brake-locking device it is necessary to move the top end of brake-lever H forward, which being pivoted to 100 arm E at slot e' forces the lower end of brake-lever H backward and to the lower ends of slots e and e', thereby placing lower end of pawl J into recess f'', ready to engage alternately

with teeth f' as brake-lever H is moved farther forward along segment F. At the same time the convexed top end of arm E traces the under concaved edge of segment F, thereby, in connection with parallel parts k and k of brake-lever H, reinforcing segment F, making it absolutely secure for pressure of pawl J as it engages in succession with teeth f' along the top edge of segment F.

10 It will be observed that as brake-lever H is moved forward it carries upper end of arm E, thus turning brake-roller A in its bearings, thereby throwing lower end of short arm a backward, which, by means of pivoted rod B, connected with brake-beam C, draws the shoes c and c against wheels D and D to any desired tension and is firmly held in place by pawl J engaging at corresponding angles with teeth f' , as provided, thus holding upper end 15 of brake-lever H in front of pivotal bearing of said brake-lever at slot e' , at the same time holding the lower end of brake-lever H to the rear of said pivotal point e' . It will be further observed that with the parts of my device placed in this locked position the common center of the two extreme points of resistance—namely, upper end of pawl J and shoes c and c —falls in front of and below the pivotal point e' of brake-lever H, thus making it impossible for my improved brake-locking device to become unlocked, as shown in Fig. 1, except by applying sufficient power to the top end of brake-lever H to force it back or to the left, as shown in Fig. 2. When 25 it is desired to unlock my device and release the brake, it is done by forcing the upper end of brake-lever H back or to the left. In so doing pawl J, with its forked concaved end fitting over the upper convexed end of whatever tooth on top of segment F it may be engaged with, answers as a fulcrum to disengage anterior prong j and to raise the brake-lever H to the highest points of slots e and e' , at which point pawl J is reversed, as shown 30 in Fig. 2, and carried back with brake-lever H and arm E to swing in recess f'' , thereby releasing brake and being ready to engage with teeth f' whenever brake-lever H is again pulled forward.

50 I call attention to the fact that inasmuch as my device is placed on the gear of wagon or vehicle and that it can be locked at any and all times by simply thrusting brake-lever forward and unlocked by thrusting it backward, which is susceptible of being done by so many different modes, depending on the kind of a load that is being hauled, any other way to operate my device except by taking hold of upper end of brake-lever H, as is here shown, or by inserting a lever into lever-rings h and h , and thereby operating it, will be left to suit the convenience of the operator.

55 I am aware that prior to my invention claims have been made for self-adjusting lever-and-pawl combinations with segment for brake-

locking devices; but none have covered the essential and practical points that I herein claim as my invention and desire to secure by Letters Patent.

Having thus described my invention, what I claim as new, and desire to secure by Letters Patent, is—

1. The herein-described arm, lever, segment, and pawl mechanism for locking and unlocking wagon and other vehicle brakes, which consists essentially of a vertical arm, having near its upper end a vertical and near its lower end a diagonal slot a pivoted brake-lever constructed of two parallel parts and two horizontal lever-rings near its upper end, a cog-toothed, flanged and recessed segment, engaging and disengaging a forked pawl J, substantially as described.

2. The herein-described locking and unlocking attachment for wagon and other vehicle brakes, consisting of a slotted arm with upper end convexed, and with lower end rigidly secured to a brake-roller, a segment rigidly secured to gear of wagon, or vehicle, so that its under edge will rest on the top convexed end of slotted arm, the front portion of upper edge of said segment, provided with angling, cog-shaped teeth, the upper ends of which are convex, with corresponding concaved spaces between the teeth, with rear portion of upper edge of said segment provided with a recess, a vertical pivoted, brake-lever constructed of two parallel parts, provided near its upper end with two horizontal lever-rings, having projections thereon, placed between and securely riveted and connected with parallel parts of brake-lever in the construction of the same, with lower end of brake-lever parts extending down on each side of said segment and arm, pivoted to said arm by means of bolts passing through slots therein, a forked pawl pivoted between parallel parts of brake-lever, so that the forked end will engage and disengage with teeth and swing in recess on top edge of segment, in a manner substantially as described.

3. The combination of arm E rigidly secured to brake-roller A, the brake-lever H constructed of rings h and h and parallel parts k and k riveted together by means of rivets i and i and pivoted to arm E by bolts i' and i' passing through slots e and e' in arm E, the segment F rigidly secured to bolster G, with under edge resting on convexed top end of arm E and extending between parts k and k of brake-lever H, the forked pawl J pivoted between parts k and k of brake-lever H, so as to engage and disengage with teeth f' and swing in recess f'' on top edge of segment F, substantially as described.

55 In testimony whereof I affix my signature.

WILBUR G. HOUK.
